CLAIM

The ornamental design for a combined relaxation and exercise chair, as shown and described.

DESCRIPTION

FIG. 1 is a front perspective view of a combined relaxation and exercise chair showing my new design;

FIG. 2 is a front elevational view thereof;

FIG. 3 is a rear elevational view thereof;

FIG. 4 is a top plan view thereof; and,

FIG. 5 is a right side elevational view thereof, the left side being a mirror image of that shown.

The bottom is plain and unornamented.

FIG. 1**FIG. 2****FIG. 3****FIG. 4**FIG. 5
